UNITED STATES PATENT OFFICE.

CHARLES ADIS PURVIS, OF VERSAILLES, MISSOURI.

DOOR OPENING AND CLOSING DEVICE.

Application filed November 1, 1923. Serial No. 672,198.

To all whom it may concern:

Be it known that I, CHARLES A. PURVIS, a citizen of the United States, and a resident of Versailles, in the county of Morgan and State of Missouri, have invented certain new and useful Improvements in Door Opening and Closing Devices, of which the following is a specification.

My present invention relates generally to door opening and closing devices and more particularly to improvements in that especially type of door opening and closing device described and claimed in my Patent 1,358,573 dated November 9, 1920; the primary object of my present invention being the provision of certain improvements upon the construction of my patented device with respect to simplicity, strength, durability and general effectiveness.

20 In the accompanying drawing which illustrates my present invention and forms a part of this specification,

Figure 1 is a sectional top plan view illustrating the practical application of my invention,

Figure 2 is a front elevation showing the doors open,

Figure 3 is a top plan view of my invention with the parts in the position shown in

30 Figure 2, and

Figure 4 is a detail longitudinal section on an enlarged scale, partially through the apparatus, showing the latch.

Referring now to these figures and particularly to Figures 1, 2 and 3 I have shown in the first two of these figures a cabinet or other similar device 10 provided with horizontally swinging front doors 11 and 12, one thereof having a handle 13, and each provided with outer vertically disposed hinges 14.

45 My invention provides for the simultaneous opening of the doors 11 and 12 when the handle 13 of the latter is drawn outwardly, as well as to hold the door stationary in the full open position and my invention also provides for the simultaneous closing of the doors upon release of a simple latch the latter of which becomes effective 50 when the doors are fully opened.

To the above end my invention proposes a pair of door controlling arms 15 and 16, the former being rigidly attached as at 17 to the inner surface of the door 11 to extend 55 at right angles to said door and the rigidity of which is insured by an angular brace 18

secured to the arm and to the door 11 as plainly seen in Figures 1 and 3. At its free end the door controlling arm 15 has a notch 19, and adjacent to its free end this arm supports a pivotal connection 20 between the same and the inner end of the door controlling arm 16 whose outer end is pivotally connected as at 21 to a bracket 22 secured to the inner surface of the door 12 at or about a central point between its side edges. The arm 16 is in two parts 23 and 24 which may have longitudinal slots 25 and an adjustable clamping bolt 26 through the slots so as to provide for lengthwise adjustment 60 of the arm 16 over all to fit doors of various widths. It is obvious that various other mechanical expedients may be resorted to for the purpose of connecting the overlapping parts 23 and 24 of the arm 16 in adjustable relation.

Near its pivot 20 with the arm 15, the arm 16 has a pair of lengthwise spaced slots 27 and 28 through the former of which the downturned free end 29 of a latch piece 30 80 projects so that when the doors 11 and 12 are swung to the open position and the arms 15 and 16 swing therewith to lengthwise aligned position, the said downturned end 29 of the latch piece 30 may slip into the end 85 notch 19 of the arm 15. The latch piece 30 is slidable on the inner end of the arm 16 by virtue of a guide bolt or rivet 31 extending therethrough and loosely through the slot 28 of the arm 16, the latch piece having 90 at its inner end an upstanding extension 32 apertured for engagement by one end of a latch controlling spring 33 whose opposite end is fixed around the pivot 20.

The doors 11 and 12 are held in closed 95 position by a door actuating spring 34 shown in Figures 1 and 2, whose inner end is anchored within the box or cabinet 10 and whose outer end is anchored to the inner surface of the door 12 adjacent to the hinged 100 edge of the latter, and when it is desired to open the doors the handle 13 is grasped and the door 12 pulled toward open position. As this movement takes place the arm 16 swinging outwardly pulls the door 11 open 105 by virtue of its connection with the inner end of the arm 15 and when the doors during this movement shift to the fully open position shown in Figures 2 and 3, the latch piece 30 becomes engaged with the free end 110 of the arm 15 so that the two arms 15 and 16 are thus locked in longitudinally aligned

position so as to form in effect a rigid brace across the space between the doors preventing the latter from swinging inwardly to the closed position under the influence of the door actuating spring 34.

To release the arms one from the other it is obviously necessary to retract the latch piece 30 against the tension of its controlling spring 33 and I have provided for this

- 10 purpose a flexible releasing connection 35 secured at one end to the upstanding extension 32 of the latch piece and extending around and downwardly over guide pulleys 36 and 37 mounted on the inner surface of
- 15 the door 12, the free end of this flexible connection depending below pulley 37 and having a terminal handle or weight 38. Thus a pull upon the handle or weight 38 has, through the flexible connection 35, the effect of pulling the latch piece 30 outwardly along the arm 16 so as to free its down-turned end 29 from the notch 19 of the arm 15. Immediately this takes place the two arms are free to flex with respect to one another and thus the doors 11 and 12 are simultaneously movable toward closed position under the tension of the door actuating spring 34.

The connections and parts constituting my present invention may thus be mounted ad-

jacent to the upper edges of the doors and will thus interfere to a minimum extent with access to the cabinet when the doors are open, and these connections and parts it is also to be noted are not only simple and inexpensive but are strong, durable and effective for the intended purposes.

I claim:

Controlling connections for oppositely swinging spring actuated doors, including an arm rigidly connected to, and projecting inwardly at an angle to, one of said doors and having a flat body, an arm having one end overlapping and pivotally connected to said first arm at a point spaced from the free end of the latter and having its other end hingedly connected to the inner surface of the other door whereby to constrain the doors to simultaneous opening and closing movements, said rigid arm having a notch at its free end beyond said pivot, a spring controlled latch member longitudinally movable on the second arm adjacent to said pivot and shiftable into said notch when the two arms are longitudinally alined in the open position of the doors, a spring controlling said latch member, and a flexible releasing connection for said latch member extending adjacent to one of said doors.

CHARLES ADIS PURVIS.
